CLYDE S. WRIGHT, OF TOLEDO, OHIO, ASSIGNOR TO THE NATIONAL SUPPLY COMPANY, OF TOLEDO, OHIO, A CORPORATION OF OHIO.

MAST-ELEVATING MECHANISM FOR PORTABLE PULLING MACHINES.

Application filed April 23, 1927. Serial No. 185,984.

My invention relates to mast elevating mechanism for portable machines for pulling sucker rods, tubing, and other devices from wells or for performing other hoisting operations.

Heretofore it has been common to provide two gin poles in erecting a mast in position at a well hole, the hoist line passing over the gin poles and down to a reel or drum mounted close to and parallel with the center bunk or swivel upon which the gin poles are mounted. The handle for operating the drum has been placed close to the end thereof and therefore so near to the base of the gin poles and the mast that the operator of the handle is liable to be injured in case the gin poles or the mast should accidentally fall.

It is one object of this invention to use a single gin pole and to lead the hoist line down through the vertical king-pin or pivot-post of the center bunk or swivel, so that the line will be perfectly free to operate, no matter what position the mast, gin pole and center bunk may assume. Another object is to attach the drum to the wagon rather than to the base or support of the gin pole, and to locate the handle at a safe distance from the gin pole and mast. My invention also embraces details and combinations which will be better understood in connection with their description.

Referring to the accompanying drawings, Fig. 1 is a side view of a pulling machine embodying my invention, a portion being broken away; Fig. 2, an end elevation of the wagon and a side view of the gin pole and mast and adjacent parts in the positions they assume after the mast has been erected, the upper parts of the gin pole and mast and adjacent parts being omitted; Fig. 3, a detail diagrammatic view showing the winding drum and the course the lower end of the hoist line takes; Fig. 4, a section on the line IV—IV on Fig. 5, the center bunk and parts adjacent thereto, parts being broken away, and Fig. 5, an elevation, the view being taken at right angles to Fig. 4, and the mast being in transverse section.

The pulling machine has not been completely illustrated to show the parts as they are in the positions they assume from the time the gin pole and mast leave their positions shown in Fig. 1 to the time the mast is ready for hoisting operations. The pulling machine shown is for the most part old and the parts shown are those closely associated with the particular portions in which my invention resides.

On the drawings, 1 designates a wagon or truck having the frame 2 which supports centrally thereof the center bunk or swivel or yoke 3 having the downwardly extending hollow king-post, swivel-post or king-pin 4 mounted to rotate on a vertical axis in the bearings 5 and 6 supported by the cross members 7 and 8 of the frame. The swivel has the upstanding arms 9 and 10 which rigidly support the horizontal hollow trunnion 11, to one end of which the usual diagonal brace is attached to brace the gin pole against lateral movement.

On the trunnion 11 and between the arms 9 and 10 I secure the cradle or saddle 14 having the arcuate seat 15 for the mast 13 when in its lowered position, which it has while the wagon 1 is moving. To one end of the saddle the gin pole 16 is pivotally mounted on the bolt 17 so that it may be swung up to a position shown in Figs. 2, 4 and 5 and down to an inclined position as shown in Fig. 1. 35' is a guy-rope for limiting the pivotal movement of the gin-pole upwardly. It is fastened to the top of the gin-pole and the lower end of the mast carriage 18 pivotally connected to the usual links 36 (only one shown) which are pivoted to the trunnion 11 in the usual or other suitable manner. The mast is connected to the carriage 18 in any suitable manner, as by the band 19. When the mast is horizontal and in place for transportation by the wagon the rear end of the carriage 18 rests on the bunk or support 20 on the front end of the wagon. A bunk or saddle 21 on the wagon at the rear of the center bunk 3 supports the rear part of the mast.

The cross-member 8 of the frame 2 sup-

ports the pendent bearings 22 between which the winding drum 23 is mounted on the shaft 24 turning in the said bearings. The drum 23 is parallel with the sides of the frame 2 and the shaft 24 extends out to the rear end of the wagon and is mounted to turn in the bearing 25 pendent from the frame 2. The rear end of the shaft has the gear 26 meshing with the pinion 27 operated by the handle 28 or other suitable means.

The hoist line 29 has one end attached to the sheave block 30 on the top of the mast 13 and runs back and forth over sheaves 31 in the block and over sheaves 32 near the top of the gin pole 16 and finally over the sheave 33, under the sheave 34 and over the sheave 35 and thence down through the king-post 4 to the winding drum 23. The sheaves 33, 34 and 35 are mounted between the arms 9 and 10 and on the bunk or swivel 3. The sheave 35 is placed preferably so that the line 29 stands centrally in the king-post. The sheave 34 is placed at one side of the periphery of the sheave 35 so as to allow the line 29 to pass upwardly at the side of the mast which lies directly over the sheave 35. The sheave 33 merely directs the line properly to the sheave 34, regardless of the position of the gin pole, the line 29 always being parallel with the gin pole.

With the parts as in Fig. 1, the gin pole and mast are erected as follows, the description being abbreviated as the general operation is well known to those acquainted with the art to which this invention belongs. When the handle 28 is turned to wind the line 29 on the drum 23, the gin pole 16, being somewhat upwardly and forwardly inclined, is caused to move up to the left on the pivot 17 and until the guy rope 35' becomes tight. Then the gin pole becomes stationary.

Next the center bunk 3 with the carriage 18, the mast 13 and the gin pole 16 and accessory parts are swung around crosswise of the frame members 2. The forward end of the swung unit being the heavier settles to the ground leaving the mast in a partly raised position and supported by the carriage 18 which is still pivotally connected by the links or side bars 36 to the trunnion 11. Upon further turning the handle 28 the mast will be raised to the position as shown in Fig. 2, this being accomplished in the usual manner which is old and well known.

By my improvements the hoist-line reel does not travel with the center bunk or swivel but has a fixed position on the wagon; the handle for turning the reel is at the end 60 of the wagon distant from the gin pole and mast and not in line with them in case they should fall; the hoist line reel is under the mast and beneath the center bunk, the sheaves being arranged so that the line 65 travels up and down in the swivel-post in

the center bunk and thence on sheaves which direct it laterally of both the mast and the gin pole; and a single gin pole is used where it is customary to have two.

I claim—

1. In a portable hoisting mechanism, a stationary frame, a hollow vertical rotary swivel post, a mast and a gin pole supported by the same, and a hoist line for the mast and gin pole, means for directing the hoist line down through the hollow of the post, and a reel carried by the frame for operating the hoist line and connected to the line to draw it down through the said hollow.

2. In a portable hoisting mechanism, a stationary frame, a hollow vertical rotary swivel post, a mast and a gin pole supported by the same longitudinally of the frame and movable with the post so as to be transverse of the frame, and a hoist line for the mast and gin pole, means for directing the hoist line down through the hollow of the post, a reel carried by the frame for drawing the hoist line down through the said hollow, and means at the end of the frame for operating the reel.

3. In a portable hoisting mechanism, a stationary frame, a hollow vertical rotary swivel post, a mast attached to and movable with the post, a saddle over the hollow in the post to support the mast in a reclining position, a gin pole movable with the post, a hoist line extending down through the hollow of the post, sheaves guiding the line laterally of the mast and to the gin pole, a stationary reel for drawing the line down through the said hollow, and means toward one end of the frame for operating the reel.

4. In a portable hoisting mechanism, a stationary frame, a hollow vertical rotary swivel-post carried thereby, a mast, a saddle carried by the post and above the same to support the mast in a reclining position, a single reclining gin pole pivotally carried by the swivel post at one side of the mast, a hoist line for raising the gin pole and the mast, means for guiding the hoist line down through the hollow of the swivel-post, and laterally of the gin pole and the mast and thence to the top of the gin pole and mast, a winding reel for the hoist line supported independently of the swivel post and arranged to draw the line down through the said hollow, and reel-operating means remote from the gin pole and the mast and arranged out of the path of the accidental falling of the same.

5. In a portable hoisting mechanism, a stationary frame, a hollow vertical rotary swivel post, a pair of upright arms on the latter, a horizontal trunnion carried by arms directly over the hollow of the post, a saddle on the trunnion, a mast pivotally connected to the trunnion and adapted to lie on the saddle, a gin pole pivotally con-

ected to this saddle, a hoist line for the mast and gin pole, sheaves guiding the line down through the hollow of the post and laterally of the trunnion, mast and gin pole, and a handle for operating the shaft, the latter extending transversely of the mast and gin pole and the handle being remote to therefrom.

5 a line reel carried by the frame and arranged to draw the line down through the said hollow, a shaft for operating the reel,

In testimony whereof, I hereunto affix my signature.

CLYDE S. WRIGHT.
